HARRY DIFLO.
By *William Webster*
ATTORNEY.

UNITED STATES PATENT OFFICE.

HARRY DIFLO, OF PHILADELPHIA, PENNSYLVANIA.

HAME-HOOK.

SPECIFICATION forming part of Letters Patent No. 683,732, dated October 1, 1901.

Application filed December 28, 1900. Serial No. 41,016. (No model.)

To all whom it may concern:

Be it known that I, HARRY DIFLO, a citizen of the United States, residing at Philadelphia, in the county of Philadelphia and State of Pennsylvania, have invented certain new and useful Improvements in Safety-Hooks for Hames, of which the following is a specification.

My invention relates to a safety-hook for hames, and has especial relation to hames for harness for fire departments or hospital, emergency, and police patrol.

The essential idea of the invention is to provide a safety-hook for attachment with the harness-trace whereby the trace may be quickly and conveniently connected with the hame and when so connected be absolutely safe from disengagement with the hook even under the trying test of a rapid run, with the attendant sudden checking of speed or quick turning of corners, and in which the trace may be conveniently disengaged from the hook when desired.

The invention consists in the parts and combination of parts hereinafter described, and pointed out in the claim.

In the drawings, Figure 1 is a front elevation of a pair of hames provided with the safety-hook. Fig. 2 is a sectional view of the hook on line XX, Fig. 3, looking in the direction of the arrow. Fig. 3 is an elevation of the hook, partly in section, this view being drawn upon an enlarged scale. Fig. 4 is a side elevation of the hook, showing the latch when disengaged and raised. Fig. 5 is a plan view of the hook, showing a modified construction.

1 designates the hame, formed with a lower ear 2 and an upper ear 3, both projecting at right angles to the hame and between which the hook 4 is pivotally secured, each ear having a hole 5, through which the bolt 6 passes and upon which the hook is pivotally fastened. Hook 4 is formed with the body portion 7 of

45 a width to pass between ears 2 and 3 and having a hole 8, through which bolt 6 passes, and from the body portion is extended to form the hook 9, the end of the hook being

bifurcated at 10 to receive the tongue 11 of a latch 12, the tongue being pivotally secured 50 to the hook by pin 13, so that the latch 12 may be swung upwardly, as shown in Fig. 4, the articulation of the parts being to allow the latch to be depressed to extend in a line parallel with the upper portion of the hook, 55 as shown in Fig. 3. The upper ear 3 is recessed, as at 14—that is to say, the recess is cut into the body of the ear at a point approximately opposite the normal position of the hook when coupled with the trace and in 60 a position for draft thereon, whereby in order to engage the trace with the hook or to disengage the same the hook must be swung upon its pivot approximately a one-half turn to allow the latch to pass from or into the recess 14.

The operation will be apparent. In order to engage the trace with the hook, the hook is turned forward toward the head of the horse upon which the harness is placed until 70 the latch coincides with the recess, when the latch may be raised, as shown in Fig. 4, and the trace may be then engaged with the hook, the latch being then depressed, passing through the recess in the ear 3, and as the 75 hook is turned to a position parallel with the body of the horse the latch passes beneath the flange of the ear and is safely locked thereby. This operation is repeated when it is desired to disengage the trace from the hook. 80

I may vary the means for introducing the latch beneath the ear—as, for illustration, the recess 14 may be dispensed with and the flange of the ear 3 cut eccentric to the pivot-bolt, as at 15, Fig. 5, the greatest eccentricity 85 being the degree of greatest depth of the recess 14, thereby allowing the latch to drop to a position to pass beneath the flange, as has been described. This and other modifications are within the scope of my invention 90 without departing from the spirit thereof.

What I claim is—

The combination with a hame of a trace-connector comprising ears projecting from the hame, a hook pivotally secured between 95 said ears and provided at its free end with a

latch pivoted thereto, said latch constructed and arranged to extend between the said ears and be confined thereby when in its closed position, a notch in the ear which is adjacent to the latch, said notch being located near the front side of the hame and adapted to permit the rocking of the latch to open the hook when the hook has been so positioned

as to bring the latch into alignment with the notch.

In testimony whereof I hereby affix my signature in presence of two witnesses.

HARRY DIFLO.
